US00D980417S

(12) **United States Design Patent** (10) **Patent No.:** **US D980,417 S**
(45) **Date of Patent:** **** Mar. 7, 2023**

(54) **BIOPSY DEVICE FOR MEDICAL USE**

(71) Applicant: **FLOWER MEDICAL CO., LTD.**,
Seongnam-si (KR)

(72) Inventor: **Hyung Jin Ko**, Anseong-si (KR)

(73) Assignee: **Flower Medical Co., Ltd.**,
Seongnam-si (KR)

(**) Term: **15 Years**

(21) Appl. No.: **35/513,082**

(22) Filed: **Jun. 7, 2021**

(80) **Hague Agreement Data**

Int. Filing Date: **Jun. 7, 2021**

Int. Reg. No.: **DM/215033**

Int. Reg. Date: **Jun. 7, 2021**

Int. Reg. Pub. Date: **Dec. 10, 2021**

(30) **Foreign Application Priority Data**

Dec. 10, 2020 (KR) 30-2020-0061294

(51) **LOC (14) Cl.** **24-02**

(52) **U.S. Cl.**

USPC **D24/114**

(57) **CLAIM**

The ornamental design for a biopsy device for medical use, as shown and described.

DESCRIPTION

1. Biopsy device for medical use

1.1 : Perspective

1.2 : Front

1.3 : Back

1.4 : Left

1.5 : Right

1.6 : Top

1.7 : Bottom

1.8 : Enlarged

The dashed broken lines in the drawings show portions of the biopsy device for medical use that form no part of the claimed design; the dot-dash broken lines in the drawings show boundaries that form no part of the claimed design.

1 Claim, 8 Drawing Sheets
